INVENTOR -

Albert Latham
By his Attorney
Nelson W. Howard

UNITED STATES PATENT OFFICE.

ALBERT LATHAM, OF BEVERLY, MASSACHUSETTS, ASSIGNOR TO AMERICAN BUTTON & FASTENER CO., OF AUGUSTA, MAINE, A CORPORATION OF MAINE.

REEL.

Application filed November 6, 1919. Serial No. 336,042.

To all whom it may concern:

Be it known that I, ALBERT LATHAM, a citizen of the United States, residing at Beverly, in the county of Essex and State 5 of Massachusetts, have invented certain Improvements in Reels, of which the following description, in connection with the accompanying drawings, is a specification, like reference characters on the drawings indicating like parts in the several figures.

This invention relates to reels, it more particularly concerning devices of this character adapted for packing for shipment or other handling, such articles as fasteners 15 mounted upon a strip, as illustrated in the Patent No. 1,147,382, issued July 20, 1915, to William E. Elliott.

Objects of the invention are to provide a reel which will add little to the cost of 20 the package, will well protect the contained articles, and will permit them to be utilized readily.

A feature of the invention consists in a reel having a body portion, preferably provided with means to receive a winding 25 spindle, and carrying a head fixed against movement on it, upon which head an enclosing portion is separably mounted. The head determines the proper relation of the 30 contents of the reel to the body, both in the preparation and utilization of the package; while the enclosing portion guards said contents against injury or disturbance during intermediate periods. Preferably, the enclosing portion, which may be in the form of 35 a ring at the periphery of the reel, is held to the head by a depression which receives the edge of an inclined portion of the head. This arrangement facilitates the assembling 40 and disassembling of the parts, while holding them firmly in the formation of the package.

A further feature lies in a novel arrangement of the separable head co-operating 45 with the peripheral enclosing portion which is mounted upon the fixed head, said head and enclosing portion being provided with means for preventing their separation. This completes the reel structure, which 50 thus may readily be built up from inexpensive material to fully enclose the contents. I have herein shown this separable head as providing a cover having a flange to extend outside the periphery of the ring.

Still another feature of the invention involves a flexible securing member attached to one of the elements of the reel and co-operating with the others in a novel manner to maintain them assembled. With a reel including a separable head and a peripheral enclosing portion, as already outlined, the securing means holds the head upon the enclosing portion. In illustrating my invention, I have disclosed a core with fixed and separable heads and a peripheral ring, 60 there being a cord secured to the separable head, this cord passing over the ring and fixed head and being attached to means carried by the separable head. This furnishes an exceedingly simple and effective 65 means for releasably holding the elements in association.

In the accompanying drawing, illustrating one of various embodiments of my invention, Fig. 1 shows the reel in broken perspective; and

Fig. 2 is a similar view disclosing steps in the assembling and disassembling of the elements.

A central body or core 10, which may be of wood, has a main cylindrical portion at its center, and reduced end portions 12, 12 aligned with one another axially and situated concentrically with reference to the main portion. At the axis of the core is an opening 14, the purpose of which will later appear. Contacting with one end of the core, and with the portion 12 at this extremity extending through an axial opening in it, is a head 16, preferably of some such material as pasteboard, fixed to the end wall of the core by tacks 18 or other convenient means. The diameter of this head is such that it will serve to retain in place upon the core, by contact with its edge, a mounting strip 80 M, having spaced along it such fasteners or other objects as buttons B assembled with staples S, this strip being wound upon the core in a coil of suitable length. The inner end of the strip M may be fastened to the core by insertion in a transverse slot 20 in the circumference of the main portion. The outer edge 22 of the head 16, over a relatively narrow area, is inclined at an angle, say of about 45 degrees, to the general plane of the head. This edge is adapted for engagement with and retention by a circumferential groove 24, which may be V-shaped in 85 90 95 100 105

cross-section, formed at the inside and near one edge of a ring 26. This ring is preferably of pasteboard and is substantially equal in width to the length of the body portion 5 of the core. Over the free edge 28 of the ring fits the flange 30 of a separable head or cover 32, which may also be of pasteboard. At the center of the cover is an opening, through which the portion 12 at this end of 10 the core passes. The cover rests against the extremity of the body of the core, coming into close proximity with the edge of the coiled package strip and acting, with the head 16, to retain it against lateral movement. Between the center and flange of the cover is mounted securing means, as a tension fastener disk 34', which holds fast to the cover a cord or other flexible member 36. This cord is passed over the cover flange, 20 the adjacent portion of the ring and across the head 16 and diametrically opposite side of the ring and flange to a second disk 38, placed upon the cover similarly to the disk 34 but at the opposite side of the axis. 25 About these disks the cord may be wound to retain it in engagement with the elements of the reel, yet permitting it to be easily disengaged. To hold the cord against displacement circumferentially of the reel, it passes 30 through opposite depressions 40, 40 in the edge of the ring 26 outside the groove 24. These depressions are preferably of such depth that they extend into proximity with the inclined edge 22 of the head 16. When 35 so related, the cord aids the frictional engagement between the edge of the disk and the groove 24 in preventing separation of the ring and this head 16.

Fig. 2 of the drawing may be considered 40 to illustrate conditions attending both the preparation and utilization of the package including my improved reel. The core 10 with its fixed head 16 is mounted upon the spindle A of a winding machine, abutting 45 against a shoulder thereon. Against the opposite side of the core a temporary head H is held by a nut C threaded upon a reduced end portion of the spindle. Thus arranged, the complete coil is formed upon 50 these portions of the reel and the head H removed. The ring is now placed about the coil and forced in the direction of the short arrow until the inclined edge 22 of the fixed head is seated in the groove 24. This engagement is facilitated by the inclination of the edge, which permits it to yield inwardly so that the diameter of the head is 55 reduced for admission to the groove. Movement of disengagement, however, is resisted 60 by the tendency of the inclined edge to expand when pressure in the opposite direction is put upon it. The cover 32 may now be slipped over the ring and these elements secured to each other and to the head 16 by 65 drawing about them the cord 36 and secur-

ing its free extremity beneath the disk 38. In this form, the package may be shipped and will endure rough handling to any extent short of crushing it, without injury to the contents. When the fasteners are to be 70 used, as at an attaching machine, the cord is freed, the cover removed, and, with the reel with the head H fixed in place upon the spindle of the machine, the bottom of the ring 26, as viewed in Fig. 2, is pressed in 75 the direction of the long arrow at the left of the figure, this causing the inclined edge 22 to easily slide inwardly through the ring, it being deflected toward the axis for movement in this direction. When the ring is 80 nearly or quite freed from the head at the bottom, the opposite or upper side may be swung down, as indicated by the long arrows at the top and right of the figure, and removed from the reel at the bottom. The 85 strip is now ready for unwinding to allow the buttons carried thereby to be used.

Having described my invention, what I claim as new and desire to secure by Letters Patent of the United States is:—

1. A reel comprising a body constructed and arranged to receive material wound upon it and having means to receive a winding spindle, a head carried by and fixed against movement on the body and an enclosing portion separably mounted upon the head.

2. A reel comprising a core, a head secured thereto, and a ring having a depression to separably receive the head, said depression having generally V-shaped walls surrounding and converging outwardly from the core.

3. A reel comprising a core, a head secured thereto, and a ring having a depression to receive the head, said depression and head being arranged to facilitate their cooperation upon assembling movement in one direction and to resist their separation by movement in the opposite direction.

4. A reel comprising a core, a head secured thereto and provided with an inclined edge, and a ring having a depression to receive said edge.

5. A reel comprising a core, a head secured thereto and provided with an outwardly inclined edge, and a ring having a depression to receive said edge.

6. A reel comprising a core having at its ends reduced portions, a head surrounding a reduced portion and fixed against movement with respect to the end of the core, a ring mounted on the edge of the fixed head and extending toward the opposite reduced portion, and a head surrounding said opposite reduced portion of the core and held thereby against radial movement, said head having a flange extending over the ring.

7. A reel comprising a core, a head fixed to the core, a peripheral ring carried by the

fixed head, a head separably mounted upon the ring, a cord secured to the separable head and arranged to pass about the ring and fixed head, there being means provided upon the ring to retain the cord, and means carried by the separable head to which the cord may be attached.

8. A reel comprising a core, a head fixed to the core, a peripheral ring carried by the fixed head, a head separably mounted upon the ring, a cord secured to the separable head and arranged to pass about the ring and fixed head, there being a depression in the edge of the ring adjacent to the fixed head to receive the cord, and means carried

by the separable head to which the cord may be attached.

9. A reel comprising a core, a head fixed to the core, a peripheral ring carried by the fixed head, a head separably mounted upon the ring, a cord secured to the separable head and arranged to pass about the ring and fixed head, there being a depression in the edge of the ring extending into proximity with the fixed head to receive the cord, and means carried by the separable head to which the cord may be attached.

In testimony whereof I have signed my name to this specification.

ALBERT LATHAM.
